UNITED STATES PATENT OFFICE.

LEONARD L. CONKEY, OF LAWRENCE, MICHIGAN.

ACETYLENE-GAS GENERATOR.

1,247,934.

Specification of Letters Patent. Patented Nov. 27, 1917.

Application filed February 23, 1915. Serial No. 9,985.

To all whom it may concern:

Be it known that I, LEONARD L. CONKEY, a citizen of the United States, residing at Lawrence, Michigan, have invented certain new and useful Improvements in Acetylene-Gas Generators, of which the following is a specification.

This invention relates to improvements in acetylene gas generators.

10 The objects of this invention are:

First, to provide in a structure of the class described, an improved measuring and feeding device actuated by the movement of the gas bell which delivers at proper intervals with certainty a definitely measured quantity of carbid into the generator chamber.

Second, to provide improved connections with the gas bell for actuating said measuring and feeding device.

Third, to provide an auxiliary carbid supply for use when the main carbid magazine is emptied, and an improved means for discharging the contents thereof into the main carbid magazine.

Fourth, to provide a container carrying a supply of carbid for priming the generator and means for discharging said supply into the generator chamber when the auxiliary carbid supply is discharged into the main carbid magazine.

Fifth, to provide an improved acetylene gas generator and improved carbid feeding devices therefor which are simple and durable in construction and which can be easily operated and to provide means for feeding an auxiliary supply of carbid to the generator without permitting the escape of gas.

Sixth, to provide improved means for removably supporting the carbid magazine.

Further objects, and objects relating to details and economies of construction and operation will definitely appear from the detailed description to follow.

45 I accomplish the objects of my invention by the devices and means described in the following specification. The invention is clearly defined and pointed out in the claims.

50 A structure constituting a preferred embodiment of my invention is illustrated in the accompanying drawing forming a part of this specification, in which:

Figure I is a vertical, sectional view through an acetylene gas generator constructed in accordance with my invention,

the carbid magazine and feeding device being shown in full lines.

Fig. II is an enlarged bottom plan view of the carbid feeding and measuring device. 60

Fig. III is an enlarged detail sectional view through the carbid feeding device and the lower end of the main carbid magazine taken on a line corresponding to line 3—3 of Fig. II. 65

Fig. IV is an enlarged, detail view in side elevation corresponding to a part of Fig. I, of the carbid feeding device, the parts being shown by dotted lines in the position they assume before delivering a fresh charge of 70 carbid to the generator.

Fig. V is an enlarged, detail view in side elevation showing the other side of the carbid feeding device.

Fig. VI is an enlarged, detail, fragmentary, sectional view taken on a line corresponding to the line 6—6 of Fig. I, showing in detail the valve for controlling the auxiliary carbid supply and the carbid supply for priming the generator. 75

Fig. VII is an enlarged, detail, sectional view, taken on a line corresponding to the line 7—7 of Figs. I and VI, and showing in detail the container for the carbid supply for priming the generator and the valve for closing the same. 80

Fig. VIII is an enlarged, detail, sectional view on the line 8—8 of Figs. I and VI, showing in detail the pivot for the auxiliary carbid supply valve. 90

Fig. IX is an enlarged, detail, fragmentary, sectional view, on the line 9—9 of Fig. I, showing in detail the top of the main carbid magazine and the cover for the same.

In the drawing, similar reference characters refer to similar parts throughout the several views, and the sectional views are taken looking in the direction of the little arrows at the ends of the section lines. 95

Considering the numbered parts of the 100 drawing, my improved acetylene gas generator comprises a generator chamber formed by the cylindrical casing 3 having an enlarged base portion 4, and the cylindrical outer casing 1, the diameter of which 105 is somewhat greater than that of the upper portion 3 of the generator chamber. The lower end of said outer casing 1 rests upon and is secured to the base portion of the generator chamber, as shown in Fig. I. 110 The casing 1 is provided with a removable cover 2 through which access may be had

to the generator chamber. A gas discharge pipe 5 passes through the side walls of the casings 3 and 1 and the generated gas passes out of the chamber through this pipe. The 5 space between the lower portion of the outer casing 1 and the upper portion of the generator casing 3 is filled with water and forms an annular water chamber in which the lower portion of the cylindrical gas bell 10 21 is disposed, said water chamber forming a seal to prevent the escape of gas, while the gas bell 21 can rise and fall with the rise and fall of the gas pressure within.

The main carbid magazine 6 has secured 15 thereto a plurality of hooks 6' which engage the upper edge of the generator casing 3 so that said carbid magazine is centrally supported within said generator chamber. The carbid magazine has a conical shaped 20 bottom provided with a discharge opening and the conical casting 8 is secured to the lower end thereof, as shown in Fig. III, said casting being provided with a central discharge opening 9. Hanger arms 10 extend downwardly from the casting 8 and carry a journal rod 12 on which the carbid feed cylinder 11 is mounted. This carbid feed cylinder is provided with four feed 25 pockets 13 of uniform dimensions and symmetrically arranged within said cylinder. A ratchet wheel 14 is secured to one end wall of said cylinder and provided with four ratchet teeth, there being one ratchet tooth 30 for each feed pocket. A lever arm 15 is journaled on said rod 12 between the ratchet wheel 14 and the hanger arm 10, said lever arm having a weighted end 17 and being connected at the other end to an actuating rod 16 by means of which said lever arm 35 is rocked in one direction. Said lever arm 15 is provided with an arm 18' which extends at right angles thereto from its pivot. A pawl 18 is pivoted on the outer end of 40 said arm 18', said pawl being adapted to engage the teeth of the ratchet wheel 14 as the lever 15 is rocked on its pivot so as to cause the cylinder 11 to rotate and discharge carbid from the feed pockets 13 into the generator chamber. Upon the other 45 end of the cylinder 11, there is secured the ratchet wheel 19 provided with teeth corresponding to the feed pockets and the pawl 20 pivoted on the hanger arm 10 is adapted to engage the teeth of said ratchet wheel 19 50 to prevent the cylinder from turning backward. An arm 15'' extends laterally from the rear end of the lever arm 15, adjacent the weight 17, and said arm has a portion 15' extending parallel to the lever arm 15 55 and journaled on the rod 12.

An auxiliary carbid magazine 22 is carried by the gas bell 21 and is adapted to contain an auxiliary supply of carbid to be used in case the contents of the main magazine should be exhausted at a time when it

is inadvisable or inexpedient to fill the same. It very often happens that the main carbid magazine becomes exhausted during the evening and, in order to fill the same, it is necessary to remove the gas bell so that 70 acetylene gas escapes and dangerous explosions often occur because of the ignition of this gas by the flame of a lantern or light which happens to be used in filling the magazine. It is to obviate such accidents 75 that this auxiliary supply of carbid is provided. The lower end of this auxiliary magazine 22 is open but it is normally closed by a valve, as shown in Fig. VI. The plate 80 24 is pivoted on the pin 25 and has a portion 26 at one end carrying a pad of felt 27 which engages the lower end of the magazine 22 to close the same and thus normally prevents the discharge of carbid from this auxiliary feed hopper. The pivot pin or 85 bolt 25 carries a compression spring 25' which engages the plate 24 and tends to prevent the movement of the same on its pivot. A container 23 is secured to the under side of the top of the gas bell 21, as shown in 90 Figs. I and VI, and provided with an opening in its lower side. This container 23 is adapted to contain a small supply of carbid and the opening therein is normally closed by the end of the plate 24. The actuating 95 rod 16 extends upwardly through a guide tube provided in the main carbid hopper, as shown in Fig. I, the lower end of said actuating rod being bent laterally and secured to the end of lever arm 15, as has 100 already been pointed out. Curved guide members 29 are secured to the lower surface of the gas bell 21 in line with the top of the actuating rod 16 which, when the gas bell is in its lower position, is disposed 105 between said guide members. A roller 28 is disposed on said actuating rod 16 in position to be engaged by the edge of the plate 24 when the gas drum is rotated. When the gas bell rises, due to the evolution of gas 110 after the discharge of carbid into the generator chamber, the weight 17 actuates the lever arm 15 to carry the pawl 18 to a position such as shown by dotted lines in Fig. IV. This movement also carries the actuating 115 rod 16 upwardly. When the gas bell lowers, as the gas pressure decreases, the top thereof engages the top of the rod 16 forcing the same downwardly and giving the carbid feed cylinder 11 a quarter turn so 120 as to discharge the carbid which has been delivered into one pocket and to bring the next pocket into line to receive a fresh supply of carbid. A curved guard or chute 125 30 is secured to the gas bell adjacent the container 23 and directs the carbid from the container 23 inwardly onto the cover 31 of the main carbid magazine so that it will pass down into the generator chamber.

The main carbid magazine is provided 130

with a removable cover 31 having a central funnel-like depression with a central opening 32 in line with the auxiliary carbid magazine 22 and through which the carbid from said auxiliary magazine is discharged into the main carbid magazine. A bail or handle 34 is secured to the top of the gas bell 21 and extends upwardly within the casing 1 to a position such that it may be readily reached from the top of the casing 1 when the cover 2 is removed. A guide rod is secured to the top of the auxiliary magazine 22 and the bail 34 is strengthened and stiffened by said guide rod 35.

From the description of the parts given above, the operation should be very readily understood. The lower part of the generator chamber is filled with water. The cover 2 may be removed from the top of the cylindrical casing 1 and the gas bell 21 may be removed by lifting upwardly on the bail 34. This carries with it the auxiliary magazine 22 and the valve controlling the same and the container 23 holds the supply of carbid for priming the generator. The main carbid magazine 6 may be removed by lifting the hooks 6' from their support on the upper edge of the casing 3 so that the magazine and carbid feed cylinder 11 may be removed. In the operation of the device, when a fresh charge of carbid is introduced into the generator and acetylene gas is evolved, the gas bell 21 rises, allowing the actuating rod 16 to rise under the influence of the weight 17 on the lever arm 15 so that the lever arm 15 moves to the position shown in dotted lines in Fig. IV carrying the pawl 18 into engagement with the next adjacent ratchet tooth. The cylinder 11 and the feed pockets 13 are in the position shown in Fig. III. The pocket 13 which is adjacent the opening 9, having been filled with carbid passing downwardly through the opening 9 from the main carbid magazine, when the pressure of the gas within the gas bell on the generator chamber decreases and the gas bell falls so that the top thereof engages the upper end of the rod 16 and forces the same downwardly. The pawl 18, engaging the tooth of the ratchet wheel gives the cylinder 11 a quarter turn so that the filled feed pocket is emptied into the generator chamber and another feed pocket is brought into line to be filled. It will thus be seen that each time the gas bell falls to a predetermined point a measured quantity of carbid is dumped into the generator chamber.

In case the main carbid magazine 6 should become emptied, the auxiliary carbid magazine 22 can be brought into service. The flow of carbid from this hopper is controlled by the plate valve 24. By grasping the bail 34, the gas drum 21 may be rotated. This causes the edge of the plate 24 to engage the roller 28 on the upper end of the rod 16 so

that the plate 24 is turned to one side on its pivot 25. This opens the auxiliary magazine 22 and allows the supply of carbid contained therein to pass down through the funnel 32 into the main carbid magazine 6 70 and into the feed pocket 13 which is in line with the discharge opening 9. At the same time, the plate 24 moves away from the opening in the container 23 and allows the carbid contained therein to be discharged into the generator chamber. The curved guard 30 deflects this carbid inwardly so that it will not fall into the water chamber between the casings 3 and 1. This carbid, which is supplied from the container 23, acts 80 to prime the generator in that it generates enough gas to lift the gas bell so that on the next descent thereof, the carbid contained by the feed pocket 13 will be discharged into the generator chamber.

It will be observed that, in this way, I have provided an effective auxiliary carbid supply which can be brought into play by simply rotating the gas bell a short distance. This is accomplished without escape of gas 90 thus obviating any danger of an explosion. This is desirable in view of the fact that the supply of carbid is almost invariably exhausted in the evening when the main magazine cannot be refilled without a great deal 95 of difficulty and some danger due to the escape of gas.

I am aware that the particular embodiment, which I have here shown and described, is susceptible of considerable variation without departing from the spirit of my invention, and, therefore, I do not wish to be restricted to the same. I have found, however, that this form is to be preferred and, therefore, I desire to claim the same 105 specifically as well as broadly as indicated by my appended claims.

Having thus described my invention, what I claim as new and desire to secure by Letters Patent, is:

1. In a gas generator, the combination of a generator casing with a generator tank in the bottom thereof, an outer casing surrounding the upper part of said generator casing, and forming an annular water chamber between said generator casing and said outer casing, a cylindrical gas bell having its lower edge disposed in said annular water chamber, a main carbid magazine within said gas bell with discharge opening 120 at the bottom, supporting means therefor, a vertical guide tube through said magazine, a carbid feeding and measuring device carried by the lower end of said magazine, an actuating rod connected with said feeding 125 device and extending upwardly through said guide tube of such length that it is acted upon by the bell when in lowered position, a pair of guide members on said gas bell disposed to receive the upper end of said rod 130

when the bell is in lowered position, a cover for said magazine having a central opening therein, an auxiliary carbid magazine carried by said gas bell and provided with an open lower end delivering into said carbid magazine through said central opening, a reserve supply box for carbid carried by said gas bell and provided with a discharge opening at the bottom disposed to deliver 10 outside the main magazine into the tank below, a plate pivotally mounted on a vertical pivot disposed within and carried by said gas bell and having one end normally closing the opening in said reserve supply box, 15 the edge of said plate being disposed to coact with the upper end of said actuating rod when the bell is in lowered position, a guard plate secured to said gas bell adjacent said box and inwardly and downwardly directed 20 to deliver the reserve carbid direct to the generator tank to prime the generator, and a cross handle secured to the top of said gas bell whereby the same may be rotated, coacting as described for the purpose specified.

2. In an acetylene gas generator, the combination of a generator casing with tank in the bottom, a gas bell or holder with a water sealing chamber for the bottom thereof, 30 of, a carbid magazine disposed and supported within said gas bell with a discharge opening at the bottom, a vertical guide tube through said magazine, a carbid feeding and measuring device at the lower end of said 35 magazine, an actuating rod therefor extending through said guide tube of such length as to be acted upon by the bell when the bell is in lowered position, guide members on said gas bell disposed to receive the upper 40 end of said rod, an auxiliary carbid magazine carried by said bell and delivering into the main carbid magazine, a reserve supply box for a priming charge of carbid carried by said gas bell with discharge opening de- 45 livering direct into the generator tank, a plate pivotally mounted on a vertical pivot disposed within and carried by said gas bell, disposed to normally close the openings in both said auxiliary magazine and said re- 50 serve supply box, positioned to coact with the upper end of said feed actuating rod when the bell is in lowered position, and a handle on said gas bell whereby the same may be rotated, coacting as specified.

5. 3. In an acetylene gas generator, the combination of a generator casing with tank in the bottom, a gas bell or holder with a water sealing chamber for the bottom thereof, a carbid magazine disposed and supported 60 within said gas bell with a discharge opening at the bottom, a vertical guide tube through said magazine, a carbid feeding and measuring device at the lower end of said magazine, an actuating rod therefor ex- 65 tending through said guide tube of such

length as to be acted upon by the bell when the bell is in lowered position, an auxiliary carbid magazine carried by said bell and delivering into the main carbid magazine, a reserve supply box for a priming charge of carbid carried by said gas bell with discharge opening delivering direct into the generator tank, a plate pivotally mounted on a vertical pivot disposed within and carried by said gas bell, disposed to normally close the openings in both said auxiliary magazine and said reserve supply box, positioned to coact with the upper end of said feed actuating rod when the bell is in lowered position, and a handle on said gas bell whereby the same may be rotated, coacting as specified.

4. In an acetylene gas generator, the combination of a generator casing with tank in the bottom, a gas bell or holder with a water sealing chamber for the bottom thereof, a carbid magazine disposed and supported within said gas bell with a discharge opening at the bottom, a carbid feeding and measuring device at the lower end of said magazine, an actuating rod therefor of such length as to be acted upon by the bell when the bell is in lowered position, an auxiliary carbid magazine carried by said bell and delivering into the main carbid magazine, 95 a reserve supply box for a priming charge of carbid carried by said gas bell with discharge opening delivering direct into the generator tank, a plate pivotally mounted on a vertical pivot disposed within and carried by said gas bell, disposed to normally close the openings in both said auxiliary magazine and said reserve supply box positioned to coact with the upper end of said feed actuating rod when the bell is in lowered position, and a handle on said gas bell whereby the same may be rotated, coacting as specified.

5. In an acetylene gas generator, the combination of a generator casing with tank in the bottom, a gas bell or holder with a water sealing chamber for the bottom thereof, a carbid magazine disposed and supported within said gas bell with a discharge opening at the bottom, a carbid feeding and measuring device at the lower end of said magazine, actuating means for said carbid feeding device, an auxiliary carbid magazine carried by said bell and delivering into the main carbid magazine, a reserve supply 110 box for a priming charge of carbid carried by said gas bell with discharge opening delivering direct into the generator tank, a plate pivotally mounted on a vertical pivot disposed within and carried by said gas bell, 115 disposed to normally close the openings in both said auxiliary magazine and said reserve supply box, and a handle on said gas bell whereby the same may be rotated and means actuated thereby to discharge the con- 120

tents of said auxiliary and priming means, coacting as specified.

6. In an acetylene gas generator, the combination of a generator casing and tank, a gas bell, a main carbide magazine with means for delivering therefrom, an auxiliary carbide magazine disposed within and carried by said bell and delivering into the main carbide magazine, a reserve supply box for 10 a priming charge of carbide carried within the said gas bell and discharging direct into the generator tank, and means for rotating

said bell and connections to said auxiliary magazine and reserve supply box for opening the same on rotating the bell, coacting 15 as specified.

In witness whereof, I have hereunto set my hand and seal in the presence of two witnesses.
